UNITED STATES PATENT OFFICE.

ANDREW SIDOLI, OF CENTRAL NYACK, NEW YORK.

PIPE-HANGER.

1,056,596.

Specification of Letters Patent.

Patented Mar. 18, 1913.

Application filed June 15, 1912. Serial No. 703,889.

To all whom it may concern:

Be it known that I, ANDREW SIDOLI, citizen of the United States, residing at Central Nyack, in the county of Rockland and State of New York, have invented certain new and useful Improvements in Pipe-Hangers, of which the following is a specification, reference being had therein to the accompanying drawing.

10 This invention relates to pipe hangers, and has for its object the production of an efficient means for suspending a pipe.

Another object of this invention is in the production of an efficient device to suspend 15 a pipe close to the ceiling and secure it by other means than the ceiling.

With these and other objects in view, this invention consists in general of certain novel constructions, combinations and arrangements of parts as will be hereinafter fully described and claimed.

Referring to the accompanying drawings, wherein:

Figure 1 is a perspective view of one form 25 of the invention. Fig. 2 is a perspective view of another form of the invention. Fig. 3 is a vertical sectional view of the device as shown in Fig. 1. Fig. 4 is a transverse sectional view of the foot as shown in Fig. 30 1. Fig. 5 is a vertical sectional view of the device as shown in Fig. 2. Fig. 6 is a transverse sectional view of the arm as shown in Fig. 2.

This device consists of a plate 10 with an 35 angle foot 11. The angle foot is provided with an upturned flange 12. A segmento-spherical socket 13 is formed on the upper face of the angle foot 11. In the socket 13 and extending at right angles to the base 40 10 is a slot 14, said slot being wider at its central portion and tapering toward its ends. Sitting within the segmento-spherical socket 13 is a ball 14' which has a threaded aperture 15 to receive the stem 16 45 of the hanger hook 17. The plate 10 is provided with apertures 18 through which screws 19 pass to secure the hanger in position.

The other form of this invention consists 50 of a plate 10 and an angle arm 20, the angle arm being provided with a segmento-spherical socket 21 on its upper face to receive the ball 14, the socket being provided with a slot 22 through which the hanger passes

similar in all respects to the slot 14. This 55 form of the invention is adapted to be used mostly in cellars where the pipes are preferably suspended close to the ceiling and the hanger can be secured to the joists.

The threaded aperture 15 receiving the 60 threaded stem 16 of the hanger hook 17 gives the hanger a vertical adjusting means. The slot 14 being wider at its central portion than the hanger hook stem gives room for a lateral movement when the heat ex- 65 pands the pipes.

There has thus been provided a simple and efficient device of the character described and for the purpose specified.

It is obvious that minor changes may be 70 made in the form and construction of this invention without departing from the material parts thereof. It is, therefore, not wished to confine the invention to the exact form shown and described, but it is wished 75 to include all such as properly come within the scope claimed.

Having thus described this invention, what is claimed is:

1. In a hanger of the class described, a 80 plate provided with a segmento-spherical socket projecting from one end, said socket having a slot therein, a ball held in said socket and provided with a threaded opening, and a hanger hook having a threaded stem engaged in said opening.

2. In a hanger of the class described, the combination of a plate provided with a segmento-spherical socket projecting from one end, a slot extending longitudinally from 90 said socket, a ball held in said socket, and a hanger hook provided with a threaded stem adjustably secured therein.

3. In a hanger of the class described, a plate, said plate having an angle foot at 95 its lower end, said foot being provided with a segmento-spherical socket on its upper face, a ball positioned in said socket, said socket having a longitudinal slot therein and a stem adjustably mounted in said ball 100 and passing through said longitudinal slot.

In testimony whereof I hereunto affix my signature in presence of two witnesses.

ANDREW SIDOLI.
